UNITED STATES PATENT OFFICE.

WILLIAM C. FORK, OF CHICAGO, ILLINOIS, ASSIGNOR TO ACME STEEL GOODS COMPANY, OF CHICAGO, ILLINOIS, A CORPORATION OF ILLINOIS.

MACHINE FOR MAKING CORRUGATED-METAL FASTENERS.

1,268,831.

Specification of Letters Patent. Patented June 11, 1918.

Application filed November 23, 1915. Serial No. 63,027.

To all whom it may concern:

Be it known that I, WILLIAM C. FORK, a citizen of the United States, residing at Chicago, in the county of Cook and State of Illinois, have invented certain new and useful Improvements in Machines for Making Corrugated-Metal Fasteners, of which the following is a specification.

The present invention is an improvement upon the machine of the Englert Patent No. 1,208,527 issued December 12, 1916. The object is to obtain improved effects in the use of rotary disk-form cutters for slicing off portions of the corrugations of a continuously advancing strip of corrugated metal. Various methods have heretofore been devised for producing the so-called "saw tooth" formation which is so highly desirable in the well-known metal fastener sometimes termed a corrugated nail, now so extensively employed in securing together pieces of wood. The Englert invention has the advantage over prior methods of providing for the continuous advance of the corrugated strip and consequently increased speed of production which is of very considerable importance in view of the fact that the article must necessarily be marketed at a low price. I purpose still further improving along this line by applying gearing to the rotary disk cutter or cutters so that they may be positively driven at a peripheral speed at least equal to that of the rotary feeding means. Thus the cutter will be able to keep pace with the rapidly advancing strip while at the same time doing the cutting under direct power beside aiding more or less in the feeding of the strip.

In the accompanying drawing forming a part of this specification I have shown a preferred form of my invention and described the same in detail in the following specification. It is to be understood, however, that the specific disclosure is for the purpose of exemplification only and that the scope of the invention is defined in the following claims.

In the drawings, Figure 1 is a perspective view on an enlarged scale of a corrugated strip, undergoing the chamfering operation, showing the cutting disks of the machine fragmentarily; Fig. 2 a plan view of the machine; Fig. 3 an enlarged end elevation thereof; and Fig. 4 an enlarged cross section of a detail.

In the drawings the same reference character is applied to each part wherever it occurs in the several figures.

The form of the frame or support is immaterial, it being only essential that it serve as a firm and rigid mounting for the cutter disks, the corrugating and feeding rolls for the strip and the driving mechanism thereof. The disks 5, 6 are mounted upon the opposite ends respectively of shafts 7, 8, shown in dotted lines in Fig. 3 by slipping them over reduced portions 9 thereof, and applying washers 10 and nuts 11 on the reduced ends of said shafts beyond the disks. The shafts are mounted in divided inclined housings 12 which are rigidly mounted upon the stand or support in any suitable manner, as shown for example, by means of the brackets 13. The inclined disks slightly overlap, as best seen in Fig. 3. Each of the shafts 8, 7 carries a worm wheel 14, 15 which is secured thereto and engages a worm 16, 17 on shafts 18, extending longitudinally of the machine, see dotted lines Fig. 2, and mounted in suitable housings 19, on the frame or support. The gear 24 on the shaft carrying the worm 16 meshes with pinion 23 on shaft 23' provided with a driving pulley 21 by which the machine may be driven from a suitable belt 22. A cross shaft 28 receives motion from said shaft 18 through the bevel pinion 27 thereof and a similar pinion 29 upon the cross shaft and drives the other worm shaft through beveled pinions 30, 31, thereby transmitting motion to the shaft carrying disk 5. The gearing is preferably such that the disks 5 and 6 are driven at the same rate of speed.

The steel ribbon or strip from which the corrugated fasteners are to be formed may, if desired, be corrugated before being fed to the chamfering machine but preferably the latter is provided with a pair of corrugating rolls 32, 33 of which the latter is driven from the former which receives its motion from a worm wheel 41 on the shaft 100 thereof and a worm 42 upon the cross shaft 28 above described. The rolls 32, 33, are mounted in a suitable housing 43 which is bolted to the bed plate at the entering end of the machine. At the exit end the machine is provided with a pair of feed rolls 36, 36 which are corrugated to correspond to the rolls 32, 33 and receive the strip from the second cutting disk. One of the rolls 36 is driven from the other, which in turn is

driven from the cross shaft 28 by a bevel pinion 39 thereon meshing with the similar pinion 38 upon a longitudinal shaft 37 which also carries a bevel pinion 40 meshing with a similar pinion upon the shaft of the driven roller 36. The rollers 36 are mounted in any suitable support which preferably, as shown in Fig. 2 of the drawings, also forms a support or guide for the corrugated strip. Any desired form of guide may be used to maintain the corrugated strip in position to be acted upon by the cutting disks. A suitable form of guide is shown on an enlarged scale in Fig. 4, in which the strip 34, being treated, is shown as maintained in the longitudinal groove 45 in the upper end of said guide. The latter is cut away as at 46 to receive the edge of the disk and permit it to operate upon the strip.

The operation of the machine is obvious from the above description. The strip 34 first enters between the corrugating rolls 32, 33 after having, if desired, been previously sharpened along the entering edge to a knife edge, and is corrugated by said rolls; thence it enters the guide 35 opposite or in registry with the first cutting disk, which guide supports the corrugated strip while one corner thereof is being sheared away. As best shown in Figs. 1 and 4, the disk shears away that corner which is located on the opposite side of the strip from the support and main body of the disk. The strip then passes to the second cutting disk, where the other corner or shoulder is similarly removed, the disk in each instance engaging the corrugated strip at or about the median line of the corrugations. From the second cutting disk the strip passes to the feed rolls 36 by which it is fed either to a cutter by which the strip is severed into fasteners of the desired length or to a reel upon which the strip may be wound for storage.

My improved machine provides a means for cheaply and continuously chamfering corrugated strips without in any manner injuring them. Obviously the cutting disks themselves after they have penetrated the strip and become frictionally engaged therewith assist in feeding the latter through the machine.

I claim:

1. In a machine for making corrugated saw-tooth metal fasteners, the combination of means for holding a corrugated metal strip upright and guiding it rectilinearly and backing up its lower edge; means for continuously advancing the strip; a rotary

cutting disk obliquely disposed above the strip-holding means with a portion of said disk that is below its axis intercepting the path of the exposed top edge of the strip centrally thereof, the cutting edge of the disk being adapted to penetrate such edge of the strip and cut through the apices of the corrugations thereof; and power-applying means for driving the disk in a direction corresponding with the advance of the strip and at a peripheral speed as fast as the advance movement of the strip. 70

2. In a machine for making corrugated saw tooth metal fasteners, the combination of means for holding a corrugated metal strip upright and guiding it rectilinearly and backing up its lower edge; means for continuously advancing the strip; rotary cutting disks obliquely disposed above the strip-holding means and reversely related one to another with portions of such disks that are below their axis intercepting the path of the exposed top edge of the strip centrally thereof, and the cutting edges of the disks being adapted to penetrate such edge of the strip, one cutting through the apices of the corrugations thereof at one side 85 and the other cutting through the apices of the corrugations thereof at the other side; and power-applying means for driving the disks in a direction corresponding with the advance of the strip and at peripheral speeds 90 as fast as the advance movement of the strip. 95

3. In a machine for making corrugated saw-tooth metal fasteners, the combination of means for holding a corrugated metal strip upright and guiding it rectilinearly and backing up its lower edge; corrugating rolls; a rotary cutting disk obliquely disposed above the strip-holding means beyond the corrugating rolls with a portion of said disk that is below its axis intercepting the path of the exposed top edge of the strip centrally thereof, the cutting edge of the disk being adapted to penetrate such edge of the strip and cut through the apices of the corrugations thereof; corrugated feed rolls beyond the disks; and power-applying means for driving the corrugating and feed rolls and cutting disks continuously and correspondingly as to direction and with a peripheral speed of the disk as fast as that of the rolls. 100
